UNITED STATES PATENT OFFICE.

ISIDORE LOUIS, OF KANSAS CITY, MISSOURI.

ROTARY TOOTH-BRUSH.

1,203,636.

Specification of Letters Patent. Patented Nov. 7, 1916.

Application filed July 19, 1915. Serial No. 40,613.

To all whom it may concern:

Be it known that I, ISIDORE LOUIS, a citizen of the United States, residing at Kansas City, in the county of Jackson and State of Missouri, have invented certain new and useful Improvements in Rotary Tooth-Brushes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to tooth brushes and has for its principal object to provide a rotatable brush which may be operated in a person's mouth to brush the teeth longitudinally with, as distinguished from transversely across, the teeth and thereby secure desirable results that it is impossible to secure with the ordinary brush having bristles fixed on a handle.

In carrying out my invention I also seek to provide a sanitary construction which may be easily and thoroughly cleansed and which embodies improved details of structure, the preferred forms of which are illustrated in the accompanying drawing where-

in:—

Figure I is a perspective view of a rotary tooth brush constructed according to my invention. Fig. II is an enlarged detail of the brush proper and its mounting, a part of the mounting being in longitudinal section. Fig. III is a cross section on the line III—III, Fig. II.

Referring more in detail to the drawings, 1 designates the frame of the brush upon which the other parts are mounted and supported, and which preferably comprise a metal bar having one end turned at right angles to the body portion to form a shoulder 2 and extended outwardly parallel to the body to form a guard 3.

The end of the frame opposite the guard constitutes the handle of the brush and in order to provide a substantial holding body and also provide for a bearing for the brush shaft I turn the handle body back parallel with the main part to form the auxiliary handle part 4, the free end 5 of which may be welded or otherwise permanently secured to the body 1. The shoulder 2, end 5, and base 6 of the handle are provided respectively with bearing apertures 7, 8 and 9, and

rotatably mounted in said bearings or apertures is a shaft 10, the outer end of which extends parallel with the guard 3; the inner end of the shaft, being provided with a screw threaded socket 12, for receiving a handle 13 that may be inserted into the socket so that it may be firmly attached to the shaft or may be removed therefrom when the brush is to be packed in a case. 65

The outer end of the shaft 10 has a socket 14 therein for receiving the shank of the brush frame and the socketed portion of the shaft is provided with radial slots 16 for receiving wings 17 on the brush shank in 70 order to lock the brush against rotary movement on the shaft while permitting the removal of the brush therefrom.

The brush proper preferably comprises a tubular body 19 having an interior web 75 20 and a pin 21 which is fixed in the brush frame and is adapted for projection into the socket 14 of the shaft 10, the pin constituting the shank of the brush frame and carrying the wings 17. 80

Fixed to and radiating from the outer surface of the brush frame 19 are bristles 23 which may be of any desirable fineness as to the bristles or to their arrangement on the frame, and which may extend to any 85 length along the frame, it being desirable, however, to extend the guard 3 beyond the end of the brush in order to protect the user's mouth, gums, tongue or lips from the bristles. 90

The arrangement described is provided in order that the brush may be removed from the shaft and the shaft removed from the handle frame when the parts are to be cleansed, or when any part is to be replaced 95 should it be tarnished or broken. In order, however, that the shaft and brush may be held against longitudinal movement and accidental displacement in the handle frame, when in use, I lock the shaft against longitudinal movement in the frame by means of a spring keeper 24, having one end fixed and the other end provided with an offset arm 25 that is seated in a groove 26 in the shaft 10 so that the shaft may revolve freely 100 in contact with the offset member while the offset member holds the shaft against longitudinal movement in the frame, the spring extending through the hollow portion of the handle with the offset arm underlying 110 the shaft and seated in the peripheral groove thereof.

In using the device, assuming the parts to be constructed and assembled as described, the user places the brush in his mouth so that the bristles are in contact with the teeth and the guard 3 lying adjacent the lip or mouth. With the parts placed as described, the bristles are held against the teeth while the user rotates the shaft 10 by turning the crank 13, to turn the brush away from the guns, the brush being freely movable about the mouth in order that all of the teeth may be cleansed. With the crank member attached to the shaft as described, the brush may be turned in any direction without danger of the crank coming off of the shaft. After the brush has been used it may be cleansed by removing the brush from the shaft and the shaft from the handle, so that all parts of the brush 20 may be reached by cleansing liquid.

It is apparent from the description and drawings that while the brush may be revolved freely with the shaft, it is held against rotary movement on the shaft by 25 the wings 17 that take into the slots in the shaft socket, so that the movement of the brush is with the shaft although it may be easily and quickly removed when the brush is to be cleansed or replaced. It is also apparent that while the device comprises a 30 number of separate, coöperating elements, it includes no small pieces, such as screws, that might become disconnected from the device and cause injury to the user.

Having thus described my invention, what I claim as new therein, and desire to secure by Letters-Patent is:—

1. The combination with a handle body, having a shoulder at one end provided with

a guard extension, having its opposite end 40 turned laterally and extended back along the body, the free end of said body being turned inwardly and apertured to form a bearing, the shoulder and transversely turned part of the body having apertures in 45 alinement with the first named aperture, a shaft rotatably mounted in said apertures, a brush on said shaft lying along the guard extension and a crank member at the opposite end of the shaft for the purpose set 50 forth.

2. The combination of a handle body, having a shoulder at one end provided with a guard extension and having its opposite end bent back to form a bearing and handle 55 grip, the end of the backturned part being turned toward and secured to the handle body, a shaft rotatably mounted in the shoulder and in the bearing portions of the handle, a crank member on said shaft, and 60 a brush on said shaft lying along the guard extension.

3. The combination with a handle member comprising a bar having a portion extended at right angles to the body to form 65 a shoulder of the body and then extended parallel with said body to form a guard, the said handle having a backturned portion at the end opposite the guard, the backturned portion and the shoulder member 70 of the handle having apertures forming bearings, a shaft rotatable in said bearings, a brush mounted on the shaft and lying along the guard, and a crank on said shaft.

In testimony whereof I affix my signature.

ISIDORE LOUIS.
